UNITED STATES PATENT OFFICE

MICHAEL W. McARDLE, OF CHICAGO, ILLINOIS

DESIGN FOR A COMBINATION SMOKING SET

Application filed September 28, 1931. Serial No. 41,251. Term of patent 7 years.

To all whom it may concern:

Be it known that I, MICHAEL W. McARDLE, a citizen of the United States, residing at Chicago, in the county of Cook and State of Illinois, have invented a new, original, and ornamental Design for a Combination Smoking Set, of which the following is a specification, reference being had to the accompanying drawings, forming part thereof.

In the drawings—

Fig. 2 is a side elevation thereof.

I claim:

The ornamental design for a combination smoking set, substantially as shown.

MICHAEL W. McARDLE.
